United States Patent Office

Des. 201,796
Patented Aug. 3, 1965

201,796

STOOL

Eleanor M. Rolley, Truckee, Calif.
(104 4th St., No. G, Broderick, Calif.)

Filed Apr. 18, 1963, Ser. No. 74,501

Term of patent 14 years

(Cl. D15—8)

FIGURE 1 is a front perspective view of my new design for a stool;

FIGURE 2 is a rear elevational view, to a smaller scale, of the stool of FIGURE 1; and

FIGURE 3 is a side elevational view thereof.

I claim:

The ornamental design of a stool, substantially as shown.
